FRISKET FRAME FOR USE IN CONNECTION WITH PRINTING PRESSES

Application filed May 31, 1927. Serial No. 195,256.

Our invention relates to frisket frames for use in connection with printing presses.

One of the objects of the invention is to provide a simple, practical and advantageous construction of frisket frames.

Another object of the invention is to provide a practical and effective arrangement for holding the paper of the frame in proper position.

10 Another object of the invention is to permit the paper to be removed and then replaced in exactly its former position.

Another object of the invention is to permit the printing element such as a cut to be 15 accurately adjusted in the press by means of the frisket frame.

In the accompanying drawings:

Fig. 1 is a plan view of a frisket frame embodying our invention and part of a 20 printing press co-operating therewith.

Fig. 2 is a cross section taken on line 2—2 in Fig. 1.

Fig. 3 is a longitudinal section through one side of the frame.

25 Referring to the drawings, we show a frisket frame 1, having a generally rectangular shape. It is provided with spring pivotal connections 2 well known in this type of device. In Figs. 2 and 3 the frame is shown upside down.

In accordance with our invention we provide a novel and advantageous arrangement for use in connection with the paper or other material commonly used in connection with 30 these frames, such paper being shown at 3 as extended across the frame.

In the arrangement shown herein for carrying out the invention, a pair of clamp bars 4—4 are provided, one on each side of the frame. These bars extend lengthwise of the frame a greater or less distance as desired, but are of sufficient length for the sheet of paper 3. Means are preferably provided for detachably connecting these bars 4—4 with the sides of the frame, so that the paper 3 may be detachably held in position by said clamp bars, but may be removed and a new sheet or strip of paper put in place by detaching the bars from the frame and then again detachably connecting the same.

In the arrangement shown, each bar 4 is provided at its end with a pin or clip 5 and the frame 1 is provided with recesses or apertures 6 to receive pins 5. Each pin 5 is preferably provided with a shoulder 7 at 55 its farther end and this shoulder 7 is adapted to engage with a shoulder 8 on the frame 1 whereby a spring clip action holding an end of the clamp bar detachably to the frame is provided. Each end of each bar being 60 preferably provided with a spring clip arrangement of this kind, each bar may be readily attached to the frame and readily detached therefrom as desired.

Each bar 4 is also preferably provided with other pins 9—9 between its ends and these pins are adapted to fit into recesses 10—10 in the bar 1. These pins 9 aid in placing the bars in their proper positions and in holding them and the paper in position, and in relocating friskets which have been removed and filed away, when they are 65 to be used again.

By this arrangement the paper may be 70 applied to the frame 1 and then the clamp bars 4—4 applied to the same, as a result of which the paper will be properly held in position as shown in Figs. 1 and 2. The edges 3^a may be torn off by tearing them 75 along the edges of bars 4. To remove the paper the clamp bars 4—4 are removed, and then the paper removed. To apply new paper, the clamp bars may be removed, and a new sheet or strip of paper put in place 80 and then the clamp bars applied. The application and removal of the clamp bars is very easily and quickly accomplished and the manipulation of the paper as desired may be quickly done.

If desired a frisket paper which has been used may be removed and then replaced in exactly the same position by applying the bars 4 and pins 9 thereon to the frisket so that the pins will occupy the same apertures 85 in the frisket, thereby insuring the frisket being located in the same position.

Furthermore, the frisket may be used so as to aid or cause a printing element such as a cut, to be located in exactly the right place 90 in the printing press for color work or the 100

like. This may be done by using more or less transparent paper in the frisket and by employing an adjustable chase or plate base in the press. By this arrangement, a proof 5 may be taken from one cut on the transparent frisket paper and then the cut may be changed and the chase or base adjusted so as to place the second cut in exactly the position of the first cut, this being done by causing 10 the frisket proof to register with the new cut.

An adjustable chase or plate base or other device for holding printing elements of any suitable construction or arrangement may be employed. One advantageous arrangement 15 for this purpose is shown in our co-pending application for devices for holding printing members in printing presses, Case No. 1, executed as of even date herewith and bearing Serial No. 194,267.

20 In Fig. 1 there is shown such an adjustable plate base 11 in connection with the frisket frame. The base 11 is shown partly in dotted lines, since it is below the frisket paper 3. This base is adjustable in accordance with the 25 invention of said other application.

The base 11 is provided with adjusting screws 12-12 and 13 and spring controlled pins 14-14 and 15-15. By this arrangement bodily adjustment, horizontal, vertical 30 and angular of base 11 may be secured so as to secure registration of proof 16 on frisket 3 with cut carried by the base 11.

It will be understood that changes and modifications may be made without departing 35 from the spirit of the invention.

What we claim is:

1. A frisket frame having side clamp bars and resilient means for detachably applying said bars to the frame.

40 2. A frisket frame having side clamp bars and attaching means therefor comprising spring clip devices on the clamp bars and apertures in the frame cooperating with said spring clip devices.

45 3. A frisket frame provided with side clamp bars having spring clip devices comprising shouldered pins, the frame having shouldered recesses into which said pins fit.

50 4. A frisket frame provided with side clamp bars having spring clip devices comprising shouldered pins, the frame having shouldered recesses into which said pins fit, said bars also having other pins adapted to 55 pass through the paper and the frame having apertures for said other pins.

5. A frisket frame provided with side clamp bars and shoulder pins for holding said bars firmly in position on the frame, said 60 frame having tapered apertures therein to receive and cooperate with the shoulders on the said pins.

6. A frisket frame provided with means for attaching frisket paper or other suitable 65 material to the frame, said means being

adapted to perforate holes through the paper in a plane perpendicular to the general face of the frame.

In witness whereof, we hereunto subscribe our names this 28th day of April, A. D., 1927.

EDWARD O. VANDERCOOK.

ROBERT O. VANDERCOOK.

FRED R. VANDERCOOK.

DAVID D. VANDERCOOK.
